UNITED STATES PATENT OFFICE.

FRANK E. P. UBERROTH, OF NEWPORT, RHODE ISLAND, ASSIGNOR TO THE GOVERNMENT OF THE UNITED STATES.

TORPEDO.

Application filed February 13, 1922. Serial No. 536,396.

To all whom it may concern:

Be it known that I, FRANK E. P. UBERROTH, a citizen of the United States, residing at Newport, Rhode Island, have invented new and useful Improvements in Torpedoes, of which the following is a specification.

This invention relates to torpedoes and more particularly to the depth control mechanism thereof.

As is well-known to those familiar with the standard torpedo used in the Navy a mechanism is provided for regulating the depth at which the torpedo travels. This mechanism or unit heretofore installed in torpedoes has, in some cases, been open to the objection that it does not always keep the torpedo at a constant and uniform depth due to leakage of the high pressure gases in the after-body of the torpedo to the mechanism as well as the increase in temperatures in the after-body, both of which affect the delicate balance control mechanism for operating the depth control engine.

It is, therefore, one of the objects of the present invention to provide a simple and practical depth control mechanism which will be more reliable and efficient than those now in use.

A further object is to provide a depth control mechanism which will, to a large extent, be unaffected by variations in pressures or temperatures in the after-body of the torpedo where this mechanism is usually located.

A further object is to provide a mechanism of the above general character which may be easily and quickly installed, having relatively few parts which may be inexpensively manufactured and conveniently assembled.

Other objects will be in part obvious and in part hereinafter pointed out in connection with the accompanying sheet of drawings showing one of the various possible modifications, and in the several views of which corresponding parts are denoted by similar reference characters.

Referring to this sheet of drawings,

Figure 1 is a vertical transverse sectional view of such parts of the mechanism as are necessary to understand the same.

Figure 2 is a horizontal transverse sectional view taken on the line 2/2, Figure 1.

Referring now to the drawing in detail, 55 5 denotes the outer shell of the after-body of a torpedo provided with a cylindrical member 6 forming with the shell 5 a chamber 7 which communicates through an opening 8 with the sea water through which the 60 torpedo travels. Secured to the member 6 by bolts 10 is a plate 11 and between the parts 6 and 11 is a water-tight gasket 12. The upper part of the member 11 is provided with a flange 13 to which is screwed a tubular or cylindrical member 14 having a removable screw cap 15 at its upper part. These members constitute an outer chamber or casing protecting the inner mechanism hereinafter described both from the high 70 65 temperatures of the after-body and the increased pressure resulting from the exhaust gases of the engine. The part 11 is also provided with an upwardly extending cylindrical flange 16 having a threaded cap 17 75 at the top provided with a gasket 18 and a downwardly extending spindle guide 20 co-acting with a recess 21 centrally disposed in a spindle 22 whereby the spindle may move up and down in a straight line under 80 the action of a tension spring 23 and a diaphragm 24, which diaphragm is secured to the member 6 and a piston 27 carried by the lower end of the spindle 22.

The lower end of the spindle 22 is threaded to accommodate the setting mechanism 28, which, in turn, is threaded upon the spindle 22. A water tight cap 30 fits over the end of the setting mechanism. The central part of the piston 27 constitutes a member 90 31 to which are secured trunnions 32 carrying the depth control arms 33 at both sides. These arms, as is well known to those familiar with the art, extend in a fore and aft direction being pivoted to a fixed support 95 at one end and having a bell crank and lever mechanism pivotally connected at the opposite end for transmitting motion of the diaphragm to the depth control engine.

Heretofore the depth setting mechanism has been set from the opposite or top side of the torpedo but in this improved form herein shown and described, it is only necessary to remove the cap 30, turn the setting mechanism by means of a socket wrench 100 or the like to move the spindle 22 up or down as desired thereby regulating the tension upon the spring 23. It is, of course,

to be understood that a suitable gage is associated with the depth setting mechanism or other means provided whereby the proper rotation of the member 28 may be determined. The cap 30 is then replaced and on launching the torpedo the hydrostatic pressure of the sea water acting through the opening 8 in the shell 5 moves the diaphragm 24 up or down according to variations in the depth at which the torpedo is traveling. This movement of the diaphragm is transmitted through the lever arms 33 as previously explained.

It is thus seen that the present invention provides a very simple and practical depth control mechanism well insulated from variations in temperature and pressure occurring in the after-body thus insuring that the torpedo will travel more effectively at the desired depth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and, therefore, such adaptations should and are intended to be comprehended with-

in the meaning and range of equivalency of the following claims.

What I claim is:—

1. In a torpedo, in combination, a member forming a chamber open to hydrostatic pressure, a diaphragm and piston therein, a spindle associated with the piston, a tension spring acting on said spindle, means for adjusting the spindle relative to the piston, a double wall air tight casing enclosing said spindle and spring and means within the hydrostatic chamber adapted to be removed for setting the mechanism.

2. In a torpedo, in combination, a member forming with the shell of the torpedo a hydrostatic chamber and provided with a central opening, a diaphragm and piston closing said opening, a member secured to the upper part of said first member having an integrally formed flange and an air tight cap across the upper part of said flange, a spindle and spring within said flange, said spindle having adjustable connection with said piston for varying the tension on said spring, said parts being enclosed in an air tight casing.

Signed at Newport, Rhode Island, this 5th day of January, 1922.

FRANK E. P. UBERROTH.
